ROOM HEATER

Henry J. De N. McCollum, Evanston, Ill.

Application June 10, 1939, Serial No. 278,421

4 Claims. (Cl. 126—110)

My invention relates generally to room heaters, and more particularly to heaters of this type having an independent heat generator.

In general, the heater comprises a heat generator, a radiator, a blower, or its equivalent, to move a combustible mixture of liquid or gaseous fuel and air through the generator and radiator, an igniter to ignite the mixture, and a fan to circulate the air in the room through the radiator and into intimate heat transfer relationship therewith.

It is an object of my invention to provide an improved room heater which may be easily started, which will continue in effective operation without attention, and which has novel automatic control and safety mechanism.

Another object of my invention is to provide such a heater with novel control and safety mechanism which automatically energizes an igniter, starts the movement of combustible mixture through the combustion chamber, starts the circulation of air through the radiator, and after the combustible mixture becomes ignited, turns off the igniter.

A further object of my invention is to provide novel control and safety mechanism which turns off the fuel supply if the air circulating fan stops, re-energizes the igniter if the flame becomes extinguished, and stops the draft blower, the air circulating fan, and turns off the fuel, if the combustible mixture is not ignited within a reasonable time.

A further object is to provide an improved room heater which is dependable, safe, economical and effective in use and economical to manufacture.

Other objects will appear from the following description, reference being had to the accompanying drawings, in which:

Fig. 1 is a front elevation of the heater with the heater casing, combustion chamber and a portion of the radiator shown in vertical section;

Fig. 2 is a vertical sectional view through the heater casing, fuel valve, and mixing chamber, the remainder of the heater being shown in side elevation;

Fig. 3 is a diagrammatic representation of the heater and an electrical circuit adapted to be used therewith; and

Fig. 4 is a diagrammatic representation similar to Fig. 3, but showing an alternative mechanism.

The heater, as shown in Figs. 1, 2 and 3 and denoted generally by the numeral 10, is comprised of a fuel and air mixing chamber 12. This

mixing chamber is provided with a Venturi throat 14, a gas inlet metering orifice 16 and air inlet openings 18, which are protected by a shield 20. Gas and air are drawn into this chamber and properly mixed to form a combustible mixture which passes through a tube 22 into the combustion chamber 24, and is there ignited either by the fire within the chamber or by an igniter 26. If it is desired to use a liquid fuel, a simple carburetor is provided with its outlet connected to the fuel supply line.

Although the igniter may take several forms, I prefer to use a heating coil of resistance wire, such as nichrome wire, which is electrically heated to a point above the flash temperature of the fuel used.

From the combustion chamber 24 the hot products of combustion pass upwardly through a radiator 28 composed preferably of finned copper tubes and into a header 30. From here the gases are conveyed outside the building through an exhaust pipe 32. To promote this flow through the combustion chamber and radiator, a motor driven centrifugal blower 34 is interposed in the exhaust pipe and maintains the whole system below atmospheric pressure. The radiator 28 is thus heated to a high temperature, and this heat is dissipated into the room by a fan 36 driven by an electric motor 38.

A room heater, as described generally above, is very efficient in its operation, and a small installation will heat a comparatively large room.

Because the entire heat producing portion of the system is sealed and operates below atmospheric pressure, carbon monoxide and other noxious gases cannot leak from the heater. If a leak should develop at any point in the apparatus, air from the room will flow into the heater, and if this leak should be sufficient to extinguish the fire, the fuel will be shut off in a manner to be pointed out later.

Since the radiator 28 is designed to operate with an air stream from the fan 36 blowing thereover whenever the radiator is hot, any failure of the fan 36, whether caused by a fault in the motor 38 or by some interference with the fan blades, may allow the temperature of the radiator and exhaust pipe to become elevated to an unsafe level.

To provide for this contingency, a valve 40 is interposed in the fuel line between the fuel and air mixing device 12 and the fuel source. This valve 40 comprises a metal cup 42 having a threaded inlet opening 44 at its center and a threaded outlet opening 46 spaced to one side

thereof. The inlet opening 44 is secured to a fuel supply line 48 by means of a nipple 50 and compression coupling 52, while the outlet opening is similarly connected to the fuel and air mixing device 12 by a tube or pipe 54.

The outward portion of the cup 42 is provided with a flange 56 which supports a flexible diaphragm 58 and an outwardly bowed cover 60. Screws 62 extend through the marginal portion of the cover 60 and diaphragm 58 and are threaded into the flange 56 to secure the cup, diaphragm and cover in assembled relation. An axially movable valve stem 64 extends through central openings 66 and 68 in the cover 60 and diaphragm 58, respectively. This valve stem 64 is secured to the diaphragm 58 by means of two nuts 70 threaded to the valve stem and positioned with one on each side of the diaphragm and tightened thereagainst to provide an air-tight seal.

The inward end of the valve stem 64 is cone-shaped at 72 and seats in a tapered valve surface provided at the inward end of the nipple 50, when the valve stem is moved axially inwardly. When at rest, the valve cuts off the fuel flow inasmuch as the valve stem 64 is urged inwardly by a compression spring 74 which surrounds the valve stem and is positioned between the inner surface of the cover 60 and the diaphragm 58.

The shaft of the fan motor 38 is carried on bearings (not shown) which permit considerable axial movement of the shaft under the influence of the thrust developed by the rotating fan 36. The rear end of this shaft has a portion 76 of reduced diameter which extends through an opening 78 in one end of a lever 80, the other end 82 of which is hinged at 84 to the lower portion of the valve cover 60. Somewhat above the hinge 84, the lever 80 is hingedly secured to the outward end of the valve stem 64 as by a bolt or pin 86 which extends through aligned openings in the valve stem and lever.

From the above it will be seen that with the apparatus at rest, the spring 74 will urge the valve into closed position and the motor shaft forwardly. In this position the fuel supply to the burner is cut off. Now, when the motor starts, the reactive force of the revolving fan 36 pushing the air forwardly will urge the motor shaft backward and open the fuel valve. Should the fan stop at any time, the spring again urges the fuel valve into closed position.

In the electrical control mechanism shown in Fig. 3, a primary circuit comprises a main line switch 114 which may be used to shut off the heater for extended periods, a thermostatically controlled mercury tilt switch of conventional design 116 which is placed in the room to be heated in a position remote from the heater and serves to start and stop the heater whenever necessary to maintain the room temperature substantially constant, and the primary 118 of a transformer 120.

The transformer is designed to give approximately seven volts in its secondary 122, inasmuch as the secondary circuit includes open contact switches which may more safely be utilized at low voltages.

The electrical control circuit depends for its operation upon two similar thermally responsive switches, one 124 mounted upon the combustion chamber housing and the other 124' secured to the igniter housing. Since these two switches

are similar, a description of one will suffice as a description of both.

The switch 124 comprises a top switch blade 128, a bottom blade 130 and a middle blade 132. Each of these blades is insulated from the others by means of insulating strips or blocks 134 and the whole is bound together by screws or rivets extending through insulating tubes (not shown) in a manner well known. The top and bottom blades 128 and 130, respectively, are resilient, while the middle blade 132 is composed of a bimetal strip so arranged that its outward end flexes downwardly toward strip 130 as its temperature rises. Each of these strips is provided with one or more contact points at its outward end arranged as follows: A contact point 136 on the lower surface of the upper strip 128, a point 138 normally in contact with point 136 and supported upon a bracket 140 secured to and in electrical contact with the outward end of strip 130, a point 142 on the lower surface of the bimetal strip 132, and a point 144 on strip 130 adapted to co-operate with point 142, but normally separated therefrom at room temperatures or somewhat thereabove.

The similar elements of similar switch 124' are as follows: top blade 128', lower blade 130', bimetal blade 132', insulating spacers 134', top blade contact 136', offset contact 138', offset contact supporting bracket 140', bimetal blade contact 142' and lower blade contact 144'.

The temperature responsive switch 124 is mounted upon the combustion chamber housing by means of a metal bracket 148, which serves to conduct heat from the housing to the bimetal blade 132. The switch 124' is similarly secured in heat conducting relation to the igniter housing so that when the igniter 26 is energized it will heat the bimetal blade 132' and deflect its outward end downwardly.

In the circuit, as shown in Fig. 3, one end of the transformer secondary 122 is grounded while the other end is electrically connected by a conductor 150 to switch blade 130. This conductor 150 also has a branch 152 leading to switch blade 128'. The top switch blade 128 has a conductor 154 secured thereto leading to the igniter 26, the other side of which is grounded. A conductor 156 connects switch blades 132 and 130', while blade 132' is grounded through the motor of the fan 38 by conductor 158, and through the motor of the blower 34 by means of a branch 160 of the conductor 158.

In operation, the main switch 114 is closed to put the heater in condition to operate. When the thermostat switch 116 closes, the transformer primary 118 is energized, thereby producing a current in the secondary 122, conductor 150, switch blade 130, contact bracket 140, contacts 138 and 136, blade 128, line 154 and igniter 26. As the igniter temperature increases, the bimetal blade 132' is heated and deflected until contact 142' touches contact 144', thus completing a circuit through the transformer secondary 122, line 150 and branch 152, blade 128', contacts 136' and 138', bracket 140', contacts 144' and 142', blade 132' and thence to ground through lines 158 and fan 38, and through branch 160 and blower 34. This energizes the blower 34 which draws a fuel and air mixture through the system, and the fan 38 which blows air over the radiator tubes and fins.

As soon as the fuel and air mixture starts to flow through the system, it is ignited by the igniter 26. The heat thus generated by the com-

bustion raises the temperature of the bimetal strip 132 and deflects it downwardly until contacts 142 and 144 touch. The closing of contacts 142 and 144 completes an alternative circuit to the fan 38 and blower 34 through conductor 150, blade 130, contacts 144 and 142, bimetal strip 132, line 156, blade 130', contacts 142' and 144', bimetal blade 132' and lines 158 and 160. On slight additional heating, the additional deflection of bimetal strip 132 urges blade 130 downwardly, thus separating contacts 136 and 138, and de-energizing the igniter 26. Additional heating of bimetal blade 132' similarly separates contacts 136' and 138'.

Though switch 124 may be so adjusted that contact points 136 and 138 separate very soon after contact is made between points 142 and 144, the similar switch 124' should be adjusted so that considerable deflection of blade 130' is necessary before points 136' and 138' separate. This is done so that the bimetal blade 132 will have time to heat and complete one alternate circuit to the fan and blower by closing contacts 142 and 144 before the other alternative fan and blower circuit is opened by separating points 136' and 138'. This delay in the separation of points 136' and 138' may be accomplished by making blade 128' with a slight downward flexure, so that because of its resiliency it will follow blade 130' downwardly for a short distance before separating therefrom.

With the heater operating as outlined above, should the fire become extinguished for any reason, the bimetal blade 132 will cool and allow the igniter to become re-energized to ignite the fuel. If the fire does not become rekindled, then continued cooling of bimetal strip 132 separates contacts 142 and 144 and de-energizes the fan and blower motors, thereby shutting off the heater system with the exception of the igniter circuit.

When the system is first started and in succession the igniter is energized and later the fan and blower are started, if the fire should fail to start within a reasonable time, continued heating of bimetal strip 132' by the igniter 26 will open contacts 136' and 138', thereby shutting off the fan and blower. This occurs because the lack of heat in the combustion chamber has resulted in the alternate motor circuit not being completed, inasmuch as points 142 and 144 remain separated at room temperatures.

The alternative circuit shown in Fig. 4 has a temperature responsive switch 162 which is similar to switch 124', excepting that it is provided with an electric heater 164 for its bimetal blade 166. This heater is placed in parallel with the igniter and is energized at the same time as the igniter. The switch 162, therefore, serves the same purpose as switch 124' and may be used in its place in the control circuit shown in Fig. 3, if desired. Its advantage is that it heats the bimetal blade more quickly and, therefore, energizes the fan and blower sooner than the switch 124', which cannot act until the igniter housing becomes heated, and this heat is conducted to the bimetal blade 132'.

The other elements of switch 162 are an upper blade 168, lower blade 170, upper blade contact 172, lower blade contact 174, lower blade offset bracket 176, offset contact 178, and bimetal blade contact 180. These elements are similar to the comparable elements of switch 124' and, therefore, need no further description here.

A second temperature responsive switch 182

replaces switch 124, and, like switch 124, is in heat conducting relation with the combustion chamber housing. This switch has an upper blade 184, a lower blade 186, an intermediate bimetal blade 188, and insulating spacers 190, all similar to comparable elements of switch 124. The contact points are differently arranged, however, and are as follows: The upper blade 184 is provided with a contact 192 on its lower surface, which at room temperature normally touches a contact 194 on the upper surface of the bimetal blade 188. On the lower surface of blade 188 a contact 196 secured thereto co-operates with, but at room temperature does not touch, a fourth contact 198 secured to the upper surface of blade 186.

The other elements in the circuit are a fan 200, a blower 202, an igniter 204, and a transformer secondary 206, all similar to comparable elements in Fig. 3.

In this circuit, energization of the transformer secondary 206 produces a current flow through conductor 208, bimetal blade 188, contacts 194 and 192, blade 184, conductor 210, igniter 204, and switch heater 164. This energization of the igniter 204 and heater 164 conditions the igniter to ignite the fuel and causes a downward deflection of switch blade 166, thereby completing a circuit to the fan 200 and blower 202 through transformer secondary 206, conductor 208, and a branch 212 thereof, switch blade 168, contacts 172 and 178, contact bracket 176, blade 170, contacts 174 and 180, blade 166 and conductor 214, which is connected to the fan 200 and blower 202 in parallel. This conductor 214 is also connected to switch blade 186 so that after combustion starts and the bimetal blade 188 becomes warmed, its downward deflection will close contacts 196 and 198 and provide an alternate circuit to the fan 40 and blower to provide energization of these units after contacts 172 and 178 have become separated by continued heating of the bimetal strip 166. This alternate circuit consists of the transformer secondary 206, conductor 208, blade 188, contacts 196 and 198, blade 186, and conductor 214, which, as has been explained, is connected to the fan 200 and blower 202.

As the bimetal blade 188 is heated and deflects to complete the alternative fan and blower circuit mentioned above, it separates the contact points 192 and 194 and de-energizes the igniter 204 and bimetal blade heater 164.

It will be appreciated that the circuit of Fig. 4 operates to accomplish the same control effects as the circuit of Fig. 3, and that, if desired, the temperature responsive switch 162 in Fig. 4 may be replaced by a switch heated by the igniter, as is switch 124' of Fig. 3.

From the above description of my heater, it will be seen that by closing a single electrical contact, the operation of the heater is initiated and that it will continue to operate automatically under full control. If, for some reason, the fuel supply should fail, the fan and blower will be shut off, while if the fan motor should stop, the fuel supply will be shut off and the blower and fan will be de-energized. If the fire should become extinguished, the igniter will be re-energized to start combustion again and if within a reasonable time combustion does not start, the fan and blower will be de-energized and the fuel supply shut off.

While I have shown and described a particular embodiment of my invention, it will be readily apparent to those skilled in the art that numerous

variations may be made therefrom without departing from the basic principles of the construction disclosed. I, therefore, desire to include in the following claims all such modifications and variations as will be readily apparent to those skilled in the art, and by which substantially the results of my invention may be attained in substantially the same way.

I claim:

1. In a heater of the class described, a radiator having inlet and outlet sides, a combustion chamber connected to the radiator inlet side, an exhaust pipe connected to the outlet side of the radiator, an air circulating means connected to the exhaust pipe to maintain said radiator and combustion chamber below atmospheric pressure, means to supply fuel to the combustion chamber under the influence of the air circulating means, a fan to blow air over the radiator, means to mount said fan for longitudinal movement under the reactive influence of air forced therefrom, and means to cut off the fuel supply whenever the fan stops, comprising a valve, means movable into one position to open the valve and into a second position to close the same, said movable means adapted to be actuated by the longitudinal movements of said fan.

2. In an internal combustion heater the combination comprising, a fuel supply line, a valve in said line, means movable into one position to open the valve and into a second position to close the same, a fan mounted for backward movement under the reactive influence of air propelled therefrom, resilient means biased to move said fan in a forward direction, and means to connect said fan to said movable means whereby backward movement of said fan moves said movable means into its said one position and forward movement of said fan moves said movable means into its said second position.

3. In an internal combustion heater the combination comprising, a fuel supply line, a valve in said line, a fan mounted upon a shaft, said shaft

being free to move translationally along the axis thereof, means for rotating said shaft and said fan, whereby the reactive force of said fan moves said shaft translationally backward when said fan is rotated, means to connect said shaft to said valve whereby backward movement of said shaft opens said valve, and resilient means to move said shaft forward and to close said valve.

4. In an internal combustion heater the combination comprising a fuel supply line, a valve chamber, in said line, having an inlet and an outlet, a flexible diaphragm closing one side of said chamber, a valve in said chamber and movable to open and close said inlet, thereby controlling the flow of fuel through said line, a stem for moving said valve, said stem passing through said diaphragm and being sealed thereto so that the presence of sub-atmospheric pressure in said valve chamber tends to cause said diaphragm to close said valve, a combustion chamber for receiving and burning fuel from said supply line, a heat exchanger for receiving the products of combustion from said combustion chamber, a vacuum producing device for withdrawing the products of combustion from said heat exchanger and for maintaining said heat exchanger, combustion chamber, and fuel supply line under less than atmospheric pressure, a rotatable shaft mounted for limited translational movement along its axis, a fan mounted upon said shaft for blowing air to be heated past said heat exchanger, means for rotating said shaft and said fan, whereby the rotation of said fan produces a reactive force which tends to move said shaft translationally backward, a lever having an arm engaging said shaft for translational movement therewith, first pivot means securing said lever in position, second pivot means securing said lever to said stem so that rearward movement of said shaft opens said valve and forward movement of said shaft closes said valve, and resilient means biasing said shaft toward its forward position.

HENRY J. DE N. MCCOLLUM.
